CLAIM

The ornamental design for a double stack multiport for making optical connections, as shown and described.

DESCRIPTION

FIG. 1 is a top perspective view of a first embodiment of a double stack multiport for making optical connections showing our new design;

FIG. 2 is a front view thereof of FIG. 1;

FIG. 3 is a rear view thereof of FIG. 1;

FIG. 4 is a right side view thereof of FIG. 1;

FIG. 5 is a left side view thereof of FIG. 1;

FIG. 6 is a top view thereof of FIG. 1; and

FIG. 7 is a bottom view thereof of FIG. 1.

FIG. 8 is a top perspective view of a second embodiment of a double stack multiport for making optical connections showing our new design;

FIG. 9 is a front view thereof of FIG. 8;

FIG. 10 is a rear view thereof of FIG. 8;

FIG. 11 is a right side view thereof of FIG. 8;

FIG. 12 is a left side view thereof of FIG. 8;

FIG. 13 is a top view thereof of FIG. 8; and

FIG. 14 is a bottom view thereof of FIG. 8.

FIG. 15 is a top perspective view of a third embodiment of a double stack multiport for making optical connections showing our new design;

FIG. 16 is a front view thereof of FIG. 15;

FIG. 17 is a rear view thereof of FIG. 15;

FIG. 18 is a right side view thereof of FIG. 15;

FIG. 19 is a left side view thereof of FIG. 15;

FIG. 20 is a top view thereof of FIG. 15; and,

FIG. 21 is a bottom view thereof of FIG. 15.

In FIGS. 1-21, the evenly-spaced broken lines are included for the purpose of illustrating environmental structure and form no part of the claimed design.
